Primary Examiner — Ricky Pham*(74) Attorney, Agent, or Firm* — Molins & Co(57) **CLAIM**

The ornamental design for a pie maker, as shown and described.

DESCRIPTION

FIG. 1 is a right perspective view of a pie maker showing my new design;

FIG. 2 is a left perspective view thereof;

FIG. 3 is a top view thereof;

FIG. 4 is a bottom view thereof;

FIG. 5 is a front view thereof;

FIG. 6 is a rear view thereof;

FIG. 7 is a left view thereof; and,

FIG. 8 is a right view thereof.

The broken lines shown in the drawings are for illustrative purposes only and form no part of the claimed design.
